UNITED STATES PATENT OFFICE.

ROBERT E. L. JANNEY, OF CHICAGO, ILLINOIS, ASSIGNOR TO THE AMERICAN STEEL FOUNDRIES, OF NEW YORK, N. Y., A CORPORATION OF NEW JERSEY.

PIVOT-PIN-RETAINING MEANS FOR CAR-COUPINGS.

No. 820,048.

Specification of Letters Patent.

Patented May 8, 1906.

Application filed January 6, 1906. Serial No 294,764

To all whom it may concern:

Be it known that I, ROBERT E. L. JANNEY, a citizen of the United States, residing at Chicago, in the county of Cook and State of Illinois, have invented certain new and useful Improvements in Pivot-Pin-Retaining Means for Car-Couplers, of which the following is a specification.

My invention relates to a device for holding in place a broken pivot-pin in a car-coupler, and concerns more particularly such retaining means for a knuckle pivot-pin. If a pin of this character is not provided with some sort of a device for maintaining its lower portion in place when the pin becomes broken, the coupler as a whole becomes inoperative to perform its function. To overcome this defect, I have devised a simple means for holding the lower part of a broken pin in place, and if the upper portion of the pin has the usual head it will be maintained in position by its head, while if it is headless the lower portion of the broken pin will also support the upper portion in operative position.

My means for holding the pin in place not only performs that function, but also acts as an indicator to disclose the condition of the pin, which is necessarily more or less out of sight, and also prevents the pin from turning.

In the accompanying drawings I have illustrated two embodiments of my invention, wherein—

Figure 1 is a side elevation of a coupler the knuckle pivot-pin of which is equipped with one species of my novel retaining means. Fig. 2 is a fragmentary view of the under portion of the coupler-head looking upward. Fig. 3 is a fragmentary elevation of the coupler-head at right angles to the view of Fig. 1. Figs. 4 and 5 are views similar to Figs. 2 and 3 of a modified form of my retaining means, and Fig. 6 is an elevation of the knuckle pivot-pin.

Referring to the drawings, the coupler has the usual shank 10 with the head 11, the latter being equipped with vertically-spaced apertured lugs 12 and 13. The knuckle 14 is pivoted on a pin 15, which passes through the apertures of lugs 12 and 13 and is supplied at its upper end with a head 16 and at its lower end, which projects a short distance below the

coupler-head, with a transverse round hole 17. Integral with the coupler-head, depending therefrom and adjacent to the lower end of pivot-pin 15 is a lug 18, having a vertical slot 19 therethrough. Through the hole 17 and slot 19 is adapted to pass a cotter-pin 20, which fits in the hole 17 more or less tightly, but loosely passes through the slot 19. When pivot-pin 15 is in its normal unbroken condition, the cotter-pin 20 is at the top portion of slot 19; but if the pivot-pin for any reason becomes broken its lower portion drops a small amount, carrying with it the cotter 20 to the lower end of slot 19, the pin 20 performing the triple function of indicating the condition of pivot-pin 15, retaining its lower broken portion in position to perform its function, and preventing rotation of the pin. An inspector examining these couplers will at once perceive that the knuckle-pin is broken when he finds that its cotter 20 is in the lower portion of slot 19.

The modified form of retaining means illustrated in Figs. 4 and 5 includes two slotted lugs 18' on opposite sides of the knuckle-pin through which and the hole 17 in the pin a cotter-pin is adapted to pass. The purpose and function of these lugs are the same as those of lug 18, but the use of two lugs makes a somewhat stronger construction.

It will be apparent that minor changes may be made in the device as described above without departing from the substance of the invention as defined by the claims. For example, the lug 18 may have an aperture of approximately the size of the cotter-pin, while the pivot-pin 15 may be slotted, the drop of the broken lower portion of the latter a small amount indicating its broken condition, this portion of the pin being retained in operative position, however, by the cotter-pin.

I claim—

1. A car-coupler having a pivot-pin with a transverse hole therein, a slotted lug adjacent to the hole in said pin, and a cotter-pin adapted to fit in the hole of said pin and in the slot of said lug to maintain said pivot-pin in place if it becomes broken and by its position in the slot indicating the condition of the pivot-pin, substantially as described.
2. A car-coupler having a pivot-pin with a

transverse hole therein near its lower end, a slotted lug on the under side of the head of said car-coupler, a cotter-pin adapted to fit in the hole of said pin and in the slot of said lug to maintain said pivot-pin in place if it becomes broken and by its position in said slot indicating the condition of said pin, substantially as described.

3. A car-coupler having a knuckle pivot-pin, a lug on the lower portion of the coupler-head, one of said parts having a hole therein, the other part having a slot, and a cotter-pin adapted to fit in said hole and slot to maintain said pivot-pin in place if it becomes broken and by its position in said slot indi-

cating the condition of said knuckle pivot-pin, substantially as described.

4. A car-coupler having a knuckle pivot-pin, a lug on the lower portion of the coupler-head, one of said parts having a hole therein, the other part having a slot, and a cotter-pin adapted to fit in said hole and slot to maintain said pivot-pin in place if it becomes broken, whereby the condition of said knuckle pivot-pin is indicated by the relative position of the parts of the device, substantially as described.

ROBERT E. L. JANNEY.
